UNITED STATES PATENT OFFICE.

JOHN W. ROCKWELL, OF WAYNESBORO, PENNSYLVANIA.

HOLDER FOR BOX-LIDS, SASHES, AND THE LIKE.

1,168,112.

Specification of Letters Patent. Patented Jan. 11, 1916.

Application filed May 11, 1915. Serial No. 27,376.

To all whom it may concern:

Be it known that I, JOHN W. ROCKWELL, a citizen of the United States, residing at Waynesboro, in the county of Franklin and State of Pennsylvania, have invented a new and useful Holder for Box-Lids, Sashes, and the like, of which the following is a specification.

This invention relates to holders designed for use in connection with hinged box lids, sashes and like structures, one of the objects of the invention being to provide a holder which will support the lid or other hinged structure in an elevated position, it being possible to shift the holder so as to release the supported structure and permit it to be lowered, the entire operation of raising the hinged structure to its open position and of releasing said structure and lowering it being performed, if desired, with one hand and without the necessity of touching the support or holder.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a side elevation of a box the lid of which is provided with a holder such as constitutes the present invention, said lid being shown in closed position. Fig. 2 is a similar view showing the lid held in open position. Fig. 3 is a side elevation of a portion of the holder showing the relative positions of the parts after said holder has been shifted to permit lowering of the cover. Fig. 4 is an enlarged section on line A—B Fig. 2.

Referring to the figures by characters of reference 1 designates a box having a hinged cover 2 and pivotally connected to the cover is a slide 3 which can be of any desired shape and size, said slide being provided with a longitudinal slot 4. The upper wall of the slot is formed with a series of notches 5, these notches being preferably located adjacent that end of the slot nearest the free end of the strip 1. A cross strip 6 bridges

the middle portion of the slot and is provided with a central stud 7 to which is secured the middle portion of a dividing strip 8 supported within the middle portion of the slot 4 and having oppositely extending spring fingers 9 and 10. Finger 10 has its free end portion curved upwardly and normally pressing against the upper wall of the slot 4 close to the free end of the strip 3, while the finger 9 bears yieldingly against the bottom wall of the slot 4 near the other end thereof. A stud 11 extends laterally from the box 1 and is fixed relative thereto, this stud projecting into the slot 4 and being of such size as to pass readily between the dividing strip 8 and the walls of the slot 4. When the cover 2 is in closed position, stud 11 is located in one end portion of the slot 4. When cover 2 is moved to open position, the strip 3 is drawn along the stud 11, the finger 9 passing under the stud and any one of the notches 5 being brought into position to receive the stud, thus holding the cover 2 in its elevated position. When it is desired to lower the cover it is merely necessary to raise the cover slightly from the position in which it is held so as thus to force the free end of finger 10 against the stud 11. Said stud will depress the finger 10, as shown in Fig. 2 and the said finger will finally snap past the stud and swing up against the top wall of the slot 4 so that by now lowering the cover 2, the stud will be received between finger 10 and the bottom wall of slot 4. During the lowering of the cover, the strip 8 will pass over the stud and the finger 9 will come against and ride over said stud until the stud finally assumes a position in that end of the slot 4 nearest the pivot of the strip 3 and as illustrated in Fig. 1.

While the improvements have been shown and described applied to a box and its lid, it is to be understood that they can also be used in connection with any structure which is hingedly mounted and which it is desired to hold in an open position. For example, sashes, skylights and the like can be provided with a holder such as described.

What is claimed is:

1. The combination with a fixed projection, and a hingedly mounted structure, of a strip pivotally connected to said structure and having a longitudinal slot into which the projection extends, the upper wall of said slot having a notch adjacent one end,

and a dividing strip mounted in the slot and having oppositely extending spring fingers yieldingly engaging the upper wall of the slot adjacent one end thereof and the lower wall of the slot adjacent the other end thereof.

2. The combination with a fixed projection and a hinged structure, of a strip pivotally connected to the hinged structure and having a longitudinal slot into which the projection extends, one wall of the slot being notched for engaging the projection to support the hinged structure in one position, and oppositely extending spring fingers mounted within the slot and bearing against the respective walls of the slot adjacent opposite ends thereof respectively.

3. The combination with a hinged struc-

ture and a fixed projection, of a strip slidably mounted on said structure and having a slot into which said projection extends, one wall of the slot being notched to receive the projection and support the hinged structure out of normal position, a cross strip bridging the slot and carried by the pivoted strip, and oppositely extending spring fingers connected to the cross strip and bearing at their free ends against the opposed walls respectively of the slot.

In testimony that I claim the foregoing as my own, I have hereto affixed my signature in the presence of two witnesses.

JOHN W. ROCKWELL.
